(57) **CLAIM**

We claim the ornamental design for a magnetic separation device, as shown and described.

DESCRIPTION

FIG. 1 is a top, front, and right-side perspective view of a magnetic separation device showing our new design;

FIG. 2 is a front elevational view thereof;

FIG. 3 is a left-side elevational view thereof, the right side being a mirror image; and,

FIG. 4 is a top plan view thereof.

The broken lines of FIGS. 1-4 illustrate portions of the magnetic separation device that form no part of the claimed design.
